UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,244,806.

Specification of Letters Patent. Patented Oct. 30, 1917.

Application filed January 14, 1913. Serial No. 741,965.

To all whom it may concern:

Be it known that I, JACOB H. WEISBROD, a citizen of the United States, residing at St. Louis, Missouri, have invented a certain 5 new and useful Improvement in Railway-Car End Constructions, of which the following is a full, clear, and exact description, such as will enable others skilled in the art to which it appertains to make and use the 10 same, reference being had to the accompanying drawings, forming part of this specification, in which—

Figure 1 is an elevational view of a car end of my improved construction.

Fig. 2 is a vertical section taken on the line 2—2 of Fig. 1.

Fig. 3 is a top plan view of the car end.

Fig. 4 is a horizontal section taken approximately on the line 4—4 of Fig. 1.

Fig. 5 is a horizontal section taken approximately on the line 5—5 of Fig. 1.

My invention relates generally to railway car end construction, and more particularly to the car end wall.

In railway cars, and particularly those designed for and used in freight service, the end portions of the car body, and particularly the end walls, are subjected to severe stresses and strains resulting from shocks 30 and vibrations, and by reason of the sudden starting and stopping of the cars and the shifting of the load or contents of the cars while the latter are in transit.

I propose to construct a car end wall from sections of sheet metal, the same being provided with pressed ribs or corrugations arranged so as to materially strengthen and stiffen the end wall and the panels thereof, thereby providing a construction which will 40 effectually resist internally or externally applied pressure and the resulting stresses and strains.

The principal object of my invention is to construct a car end wall from a plurality of sections of material, preferably sheet metal, each section being reinforced and stiffened by means of ribs or corrugations pressed in the sheet metal, thus providing a comparatively simple, inexpensive construction which can be readily utilized in connection with an ordinary car underframe and superstructure, and which end wall or plate will be effective in resisting all stresses resulting from shifting loads, ordinary

nary service shocks and vibrations, or collisions.

To the above purposes my invention consists in certain novel features of construction and arrangement of parts hereinafter more fully described and claimed.

As illustrated in the accompanying drawings, the car end is composed of a pair of main plates or sections 1 and 2 and an interposed plate or section 3, which latter is comparatively narrow. The main sections 1 and 2 are preferably formed of approximately rectangular pieces of sheet metal, and the upper edge of the top section 2 is shaped so as to conform with the shape of the car roof.

The side and lower edges of the section 1 and the side and upper edges of the section 2 are bent at right angles to the plane occupied by the main body portion of said sections in order to form marginal flanges 75 4, whereby the end wall or plate may be readily attached to the frame of the car body.

The horizontally disposed section 3 is, as heretofore stated, comparatively narrow and 80 its ends are bent rearwardly, as designated by 5 to correspond with the bent side edges of the sections 1 and 2, and are arranged for attachment to frame portions of the car body. The lower edge of the section 2 85 overlies the upper edge of the intermediate section 3, and the lower edge of said intermediate section overlies the upper edge of the lower section 1. By virtue of such construction water passing downward over the 90 exterior surface of the end wall, and dust, will not lodge in or leak through the joints between the sections 1, 2 and 3.

The sections of material forming the end wall or plate are attached to each other by 95 means of rivets 6, or like fastening devices which pass through the overlapping edges of said sections.

Each of the main sections 1 and 2 is formed with a series of vertically disposed 100 ribs or corrugations 7, the same being pressed from the material of which said sections are formed, and said ribs or corrugations are preferably deepest at their centers and gradually decrease in depth toward their 105 ends. These ribs or corrugations are preferably arranged at equal distances apart and the series of ribs or corrugations in one of

the plates are preferably in alignment with the corresponding ribs and corrugations of the other plate.

Formed in the lower plate 1 adjacent to 5 the outermost pair of ribs or corrugations are ribs or corrugations 8 which converge upwardly, and these ribs or corrugations are preferably deepest at their centers and gradually decrease in depth toward their 10 ends.

Formed in the upper section 2 and preferably in alignment with the converging ribs or corrugations 8 are corresponding ribs or corrugations 9 which converge upwardly, and these last mentioned ribs or corrugations are formed like the other ribs or corrugations,—that is, they are deepest at their centers and gradually decrease in depth toward their ends.

20 Formed in the intermediate narrow section 3 and extending practically the entire length thereof is a rib or corrugation 10 which is preferably deepest at its central portion, and which gradually decreases in 25 depth toward its ends. The intermediate section 3 which is stiffened and reinforced by the rib or corrugation 10 is rigidly fixed to the corresponding edges of the main sections 1 and 2, and thus forms a very 30 strong and rigid reinforcement for the end wall or plate at a point approximately midway between its upper and lower edges, and said end wall or plate is further reinforced and stiffened by the vertically disposed ribs, 35 or corrugations 7 and the inclined ribs or corrugations 8. Such construction provides a car end wall or plate which is very strong and durable and which is particularly effective against stresses tending to distort said 40 end wall.

My improved construction effects a considerable saving in the initial cost of construction of the car end walls in the cost of repairs and by forming the entire end in 45 sections the latter can be much more easily handled by the workmen during the formation of the ribs or corrugations and in the assembling or repairing of the structure than where an end plate or wall is formed in a 50 single large piece.

The ribs or corrugations are arranged and disposed so as to stiffen and reinforce the end wall to a maximum degree, and the impact of all internally and externally applied 55 shocks or blows and all service strains and vibrations will be transmitted directly to the underframe sills and plates forming a part of the car body frame.

It will be readily understood that minor 60 changes in the size, form and construction of the various parts of my improved car end can be made and substituted for those herein shown and described without departing from the spirit of my invention, the scope 65 of which is set forth in the appended claims.

I claim:

1. As a new article of manufacture a car end comprising a comparatively wide upper section, a comparatively wide lower section, and a comparatively narrow intermediate section, the upper edge of which intermediate section lies inside and is fixed to the lower edge of the upper section, the lower edge of which intermediate section lies outside and is fixed to the upper edge of the lower section, and said intermediate section having pressed therein a longitudinally reinforcing and stiffening rib or corrugation, thereby forming a transversely disposed reinforcement at a point substantially midway between the upper and lower edges of the car end. 70

2. As a new article of manufacture, a car end comprising a comparatively wide lower section, a comparatively wide upper section, 85 a comparatively narrow intermediate section, the lower edge of which upper section overlies the upper edge of the intermediate section, the lower edge of which intermediate section overlies the upper edge of the lower section, and each of which sections has pressed therein a reinforcing and stiffening rib or corrugation. 90

3. As a new article of manufacture, a car end comprising a comparatively wide corrugated lower section, a comparatively wide corrugated upper section, a comparatively narrow corrugated intermediate section, the lower edge of which upper section overlies the upper edge of the intermediate section, 100 and the lower edge of which intermediate section overlies the upper edge of the lower section. 95

4. A car end comprising a series of corrugated sections of sheet metal, the corrugation of one section lying approximately at right angles to the corrugation of the other sections, the lines of separation between said sections being horizontally disposed and the sections being arranged so that a watershed 105 is provided on the exterior of the car end forming a protection against the entrance of water and dust into the car through the joints between said sections. 110

5. A car end comprising a series of sections of sheet metal, each of which is provided with a pressed stiffening rib or corrugation, the rib or corrugation of the intermediate section lying substantially at right angles to the ribs or corrugations of the other sections, the joints between which said sections are horizontally disposed, and said sections being arranged so that a watershed is provided on the exterior of the car end forming a protection against the entrance of water and dust into the car 120 through the joints between said sections. 115

6. A wall structure for cars including an upper panel, a lower panel, and an intermediate panel connecting the two, said upper 125 130

and lower panels being provided with transversely extending corrugations and with obliquely extending corrugations, the transversely extending corrugations of the upper panel being disposed in alinement with the transversely extending corrugations of the lower panel, and the obliquely extending corrugations of the upper panel being disposed in alinement with the obliquely extending corrugations of the lower panel, and the intermediate panel being provided with

a longitudinally extending corrugation terminating adjacent its extremities and adapted to receive moments transmitted by the corrugations of the upper and lower panels. 15

In testimony whereof I hereunto affix my signature in the presence of two witnesses, this eighth day of January, 1913.

JACOB H. WEISBROD.
